UNITED STATES PATENT OFFICE.

FRANK H. ARMSTRONG, OF AUBURN, NEW YORK.

TYPE-WRITING MACHINE.

SPECIFICATION forming part of Letters Patent No. 717,794, dated January 6, 1903.

Application filed September 8, 1902. Serial No. 122,616. (No model.)

To all whom it may concern:

Be it known that I, FRANK H. ARMSTRONG, a citizen of the United States, residing at Auburn, Cayuga county, New York, have invented certain new and useful Improvements in Type-Writing Machines, of which the following is a specification.

My invention relates to type-writing machines, and particularly to that class in which the printing is visible to the operator.

The objects of the invention are to provide a simple and efficient lever mechanism for actuating the type-bars; to provide for the individual adjustment of the bars at their fulcrum-points to take up wear; to provide a type-writer in which any key-lever may be readily removed without removing or changing any of the others. These objects I accomplish by the construction shown in the accompanying drawings, in which—

Figure 1 is a sectional side elevation of a type-writing machine with my improvements applied. Fig. 2 is a sectional front elevation on line 2 2, Fig. 1. Fig. 3 is a detail view 25 showing the manner of securing the fulcrum-rod of the type-bars in place. Fig. 4 is a detail sectional view on line 4 4, Fig. 1; and Fig. 5 is a side elevation of one of the type-bars.

A designates the frame of the machine in the form of an open rectangle having vertical side pieces A'. The frame is provided on its inner sides with middle and rear inwardly-projecting lugs a' a², respectively. To the middle or intermediate side lugs a' are secured 35 the ends of fulcrum-bar A² and notched guide-bar A³ by means of screws or bolts a³, while similar bars A⁴ A⁵ are secured in like manner to the rear lugs a². The guide-bars A³ A⁵ lie in front of the respective fulcrum-bars A² A⁴, and their upper edges are notched or slotted 40 for the various type-bar actuating and shifting levers, and the upper edges of said fulcrum-bars A² A⁴ are rounded, as shown, to form the fulcrum-points for said levers.

A⁶ designates a front plate connected at the ends to the side pieces A' and having a curved lower edge to which is connected by a plate A⁸ or upon which is formed the segmental series of type-bar guide-lugs A⁷, across the lower

edges of all of which extends the round curved fulcrum-rod B, common to all of the type-bars C and secured at several places by screws b, which pass through lugs a⁷ on the lower edge of certain of the guide-lugs A⁷ into said fulcrum-bar. (See Fig. 3.) The spaces between the lugs of this segmental or curved series of guide-lugs A⁷ converge toward the printing-point, as shown in Fig. 2. In front of the fulcrum-rod B is a curved rest A¹⁰, corresponding to the curvature of the series of guide-lugs A⁷ and adapted to support the outer or printing ends of the type-bars C. The upper side of the rest A¹⁰ is cushioned by means of a layer a¹⁰ of leather, over which is placed a layer a¹¹ of felt or other sound-deadening material.

The type-bars C are all alike and each is provided at its rear or fulcrum end with a longitudinal slot c, having an upper opening c' to permit of its being readily inserted upon and removed from the fulcrum-rod B. The forward end of the slot c is rounded to permit an easy pivotal action of the type-bar B, and in order that wear may be compensated for and all looseness at the pivotal point be taken up I provide the rear wall or lug c² with a set-screw c³, which extends forwardly into the slot c and bears against the rear side of fulcrum-rod B. The screw c³ is held in its adjusted position by means of the nut c⁴ on its rear end. (See Figs. 1 and 5.) Every type-bar C is provided on its lower edge just in front of its axis with a depending lug c⁵, to which the upper end of a vertically-reciprocating connecting-link C' is pivotally connected. The lower ends of these links C' are provided with horizontal slots or rearwardly-opening hooks c⁶, which engage pins d, near the forward ends of the auxiliary or equalizing levers D. (See Figs. 1 and 4.) These levers D all fulcrum at their rear ends by means of rounded notches d' on their lower edges upon the rounded upper edge of the rear fulcrum-bar A⁴ and extend thence forwardly through the slotted guide-bar A⁶ and under a common retaining-bar A¹⁵, secured removably to the frame A by means of screws a¹⁵. The levers D are further provided at

their lower edge intermediate of their ends with longitudinal slots d^2 , open at their forward ends to receive pins e at the rear ends of the series of key-levers E. By means of 5 these equalizer-levers D it is possible to get an equal key-depression on keys E, no matter what their length may be. The key-levers E fulcrum between their ends on the upper rounded edge of fulcrum-bar A² after passing 10 through the slotted guide-bar A³ and are held in place by the overlying bar A¹⁶, secured removably at its ends to the frame A by means of the screws a^{16} . The key-levers E are curved 15 downwardly in rear of their fulcrum-points and then extend rearwardly to the slots d^2 of levers D, as above described. The key-levers are furthermore provided with vertically-disposed curved edges e' , against which travel pins d^4 at the forward ends of the auxiliary levers D, said pins d d^4 being provided 20 with antifriction-rollers to lessen friction in the slots c^6 and on the edge e' . (See Fig. 4.) To the outer ends of every pair of pins d d^4 is secured a plate d^5 , between which and the end 25 of the levers D are held the ends of links C' and curved edges e' of key-levers E. By this means the connection between these parts is maintained against accidental displacement, and yet any of the parts may be readily 30 connected without disturbing any other set. For instance, to adjust any type-bar it is only necessary to turn its individual screw. To remove any type-bar, turn the screw c^8 far enough to the rear to open slot at c' , then 35 draw the type-bar forwardly till it passes off of the bar B, and then remove pin d or let the pin d remain and throw link C' forwardly till its slot c^6 is vertical and then slip it up off of the pin d . The key-levers E and auxiliary 40 levers D are likewise capable of easy individual removal by first removing their retaining-bars A¹⁶ A¹⁵.

It will be seen that a blow on one of the key-levers E will throw its rear end up, which 45 in turn will raise the front end of the corresponding lever D and cause it to push up its link C', which in turn will exert a lifting action on the type-bar C, to which it is connected, and throw the type-bar upwardly and rearwardly toward the platen, as shown in dotted lines, Fig. 1. This causes less friction than would a pulling action on the heels of the type-bars.

What I claim is—

55 1. The combination with the frame provided with a fulcrum rod or bar, of a series of type-bars each having an open slot receiving the said fulcrum-rod, a set-screw mounted in the inner end of each type-bar with its inner 60 end entering said slot and engaging the fulcrum-rod, and mechanism for actuating the type-bars.

2. A type-bar provided at its pivotal point with a slot open at one side and a longitudi-

nal set-screw extending through the rear end 65 of the type-bar into the slot.

3. The combination with the frame and a vertically and rearwardly swinging type-bar pivoted at its rear end, of a key-lever fulcrummed between its ends, an auxiliary lever 70 fulcrummed at its rear end and operatively connected between its ends to the rear end of said key-lever, and a vertically-disposed link pivoted at its upper end to the type-bar in front of its axis and pivoted at its lower end to the 75 front end of the auxiliary lever, substantially as described.

4. The combination with the frame and a vertically and rearwardly swinging type-bar pivoted at its rear end, of a key-lever fulcrummed between its ends, an auxiliary lever 80 fulcrummed at its rear end and provided between its ends with a longitudinal slot, a pin extending from the rear end of said key-lever into said slot, a link pivoted at its upper end 85 to the type-bar in front of the pivotal point thereof, and having a slotted or hooked lower end and a pin projecting from the front end of the auxiliary lever into said link-slot.

5. The combination with the frame and a 90 vertically and rearwardly swinging type-bar, of a key-lever fulcrummed between its ends and curved downwardly and then rearwardly, an auxiliary lever fulcrummed at its rear end, pivotally connected between its ends to the rear 95 end of said key-lever and in sliding engagement at its front end with the curved part e' of said key-lever, a link depending from the type-bar and pivotally connected at its lower end to the front end of the auxiliary lever. 100

6. The combination with the frame having the type-bar fulcrum-rod, a series of spaced guides thereabove, front and rear fulcrum-bars in the frame-base and provided with rounded upper edges, slotted guide-bars and 105 overlying retaining-plates, of a series of type-bars provided with open slots at their rear ends receiving said fulcrum-rod and individually removable therefrom, set-screws entering the type-bar slots and bearing on the said fulcrum-rod, key-levers having rounded notches in their lower edges between their ends engaging the upper edge of the forward fulcrum-bar, a series of auxiliary levers fulcrumming in like manner at their rear ends on 110 the rear fulcrum-bar and provided with longitudinal slots between their ends, pins projecting from the rear ends of the key-levers into said longitudinal slots, links depending from the type-bars in front of their fulcrum-rod and provided at their lower ends with rearwardly-opening slots, and pins projecting 115 from the front ends of the auxiliary levers into said link-slots.

7. The combination with a type-bar pivoted 120 at its rear end to swing vertically and rearwardly, of a key-lever fulcrummed between its ends and curved downwardly and rearwardly

in rear of its fulcrum, an auxiliary lever fulcrumed at its rear end, and extending forwardly past the rear end and curved edge e' of said key-lever, a sliding pivotal connection between the rear end of the key-lever and said auxiliary lever, two pins projecting from the side of the auxiliary lever at the front end, a plate secured to said pins and projecting past said curved edge e' , and a link de-

pending from the type-bar and having its lower end hooked or slotted and in engagement with the rear one of said pins.

In testimony whereof I affix my signature in presence of two witnesses.

FRANK H. ARMSTRONG.
